W. M. HART

COOLING UNIT FOR MECHANICAL REFRIGERATING APPARATUS

Filed Jan. 28, 1927

UNITED STATES PATENT OFFICE.

WAYNE M. HART, OF DETROIT, MICHIGAN, ASSIGNEE TO ELECTRIC REFRIGERATION CORPORATION, OF DETROIT, MICHIGAN, A CORPORATION OF MICHIGAN.

COOLING UNIT FOR MECHANICAL REFRIGERATING APPARATUS.

Application filed January 28, 1927. Serial No. 124,173.

This invention relates to mechanical refrigerating apparatus, and more particularly to a combined vaporizer and water freezing unit.

An object of my invention is to provide a unit of the class described in which a container can be inserted into and removed from the interior of a refrigerant containing vaporizer without materially subjecting the refrigerant to the temperature of the air surrounding the unit.

A further object of my invention is to provide a unit of the class described in which a water freezing chamber is provided without increasing the overall dimensions, or affecting the air cooling capacity of the unit.

Further objects and advantages of the present invention will be apparent from the following description, reference being had to the accompanying drawing wherein a preferred embodiment of one form of the present invention is shown.

The drawing illustrates a vertical section view taken axially of a vaporizer having my invention associated therewith.

Referring now to the drawings, 10 illustrates a cylindrical shell which is preferably formed of copper and forms the main body of a vaporizer which is directly exposed to the air in a chamber to be maintained at a predetermined temperature. A ring casting 11 is secured to one end of the cylindrical shell, and a plate 12 is secured by studs 13 to close the opening in the ring casting. The plate is provided with an interiorly extending boss 14 and a refrigerant inlet passage 15 extends through the plate and boss. A coupling 16 is secured to the plate and is adapted to connect the passage 15 with the refrigerant supply conduit.

A suitable mechanism is provided to control the flow of the refrigerant from the passage 15 to automatically maintain a constant level of liquid refrigerant in the vaporizer. This mechanism includes a float member 17 which is pivotally mounted upon a rock arm 18 which is pivoted at 19 to the boss 14. A ball 20 is arranged to seat against the inner end of the passage 15 and its movement is controlled by a plate 21 attached to rock with the float arm 18 as the float travels with the body of the refrigerant in the vaporizer. An outlet passage 22 tends through the upper portion of the plate

12 and an outlet tube 24 extends therefrom into the vaporizer above the level of the liquid refrigerant. The vaporized refrigerant passes from the vaporizer through the passage 23 in the tube 24 and through a coupling 25 to the return conduit. A conduit 26 leads from the upper portion of the vaporizer mechanism which is affected by the pressure of the vaporized refrigerant to control the operating parts of the refrigerating mechanism.

The other end of the cylindrical vaporizer shell is closed by an end plate 27 which is soldered in leakproof relation therewith and has a central opening therethrough for the insertion and removal of a water freezing container 28. A pair of spaced parallel cylindrical shells 29 and 30 are secured by solder, or otherwise, to the end plate 27. The shells are open at their ends which are secured to the end plate, and the inner shell provides a freezing chamber into which the water freezing container can be inserted and removed from. The container carries a tray divided into sections for forming ice cubes, and an end plate 31 is attached to the container for closing the open end of the freezing chamber when the pan is inserted therein.

The space between the shells 29 and 30 forms a closed chamber which is filled with brine or a similar material of low temperature freezing qualities, and a plug 32 is provided in the shell 29 for filling purposes. The brine within the refrigerant retards the rise of its temperature relative to the temperature of air external of the vaporizer, and also prevents the air surrounding the vaporizer from contacting with the refrigerant interior of the vaporizer.

It will be understood that the refrigerant supply and return lines are connected respectively with a compressor and a condenser, and that the refrigerant is compressed, condensed and expanded during each cycle of travel in a circuit. This type of refrigerating mechanism is well understood in the art, and a further description and a showing thereof is not deemed necessary herein.

It will be seen that with the construction described, the water freezing pan can be removed temporarily without the air entering the freezing chamber effecting a rise in the temperature of the refrigerant and thus pro-

longing the inoperative periods of the moving parts of the refrigerating system. It will further be seen that with the construction described I have provided a compact vaporizer and water freezing unit without an increase in overall dimension or decrease in air cooling efficiency.

Various changes can be made in the details of construction described herein without departing from the spirit of my invention and the scope of the claims.

What I claim is:

1. In mechanical refrigerating apparatus, a cooling unit comprising a vaporizer containing volatile liquid refrigerant, a closed brine containing chamber arranged interiorly of said vaporizer and substantially submerged in the liquid refrigerant, an open end freezing chamber interior of said brine chamber, and a removable water container within said freezing chamber.

2. In mechanical refrigerating apparatus, a cooling unit comprising a vaporizer containing volatile liquid refrigerant, a freezing chamber arranged interiorly of said vaporizer and accessible from the exterior of said vaporizer, heat absorbing means entirely enclosed intermediate said chamber and the refrigerant in said vaporizer, and a removable container in said freezing chamber.

3. In mechanical refrigerating apparatus, a cooling unit comprising a vaporizer containing a volatile liquid refrigerant, a chamber arranged interiorly of said vaporizer

and accessible through an opening in a wall thereof, heat absorbing means intermediate said chamber and the refrigerant in said vaporizer, and a container in said chamber removable through the opening in the wall of said vaporizer, said container being provided with an end plate for closing the opening in the wall of said vaporizer when inserted in the chamber.

4. In mechanical refrigerating apparatus, a cooling unit comprising a vaporizer for containing volatile liquid refrigerant, a pair of spaced shells secured to a wall of said vaporizer, the space intermediate said shells being substantially filled with brine and the space interior of the inner shell forming a storage chamber, said vaporizer wall and inner shell having registering openings, and a slideable container for said storage chamber.

5. In a mechanical refrigerating apparatus, a cooling unit comprising a vaporizer casing for containing liquid refrigerant, said casing having an opening in a wall thereof, a leakproof storage chamber extending interiorly of said casing from the opening in the wall, a closed brine containing chamber surrounding said storage chamber and substantially surrounding said storage chamber, and removable means for closing the opening in the wall of said vaporizer casing.

In testimony whereof, I hereunto affix my signature.

WAYNE M. HART.
